GROUND-ROOTING TOOTH

Harry G. Livermore, 740 Roosevelt Ave., Tracy, Calif.

Filed Aug. 24, 1959, Ser. No. 57,274

Term of patent 14 years

(Cl. D39—1)

Figure 1 is a top perspective view showing the rear and left side of a ground-rooting tooth, embodying my new design.

Figure 2 is a right side elevation thereof.

Figure 3 is a perspective view taken from the front right corner thereof.

Figure 4 is a rear elevation.

Figure 5 is a front elevation.

I claim:

The ornamental design for a ground-rooting tooth, substantially as shown.
